UNITED STATES PATENT OFFICE.

PETAR BAČKO, OF FARRELL, PENNSYLVANIA.

RAIL-JOINT.

1,210,396.

Specification of Letters Patent. Patented Jan. 2, 1917.

Application filed September 21, 1916. Serial No. 121,462.

To all whom it may concern:

Be it known that I, PETAR BAČKO, a subject of the King of Hungary, residing at Farrell, in the county of Mercer and State 5 of Pennsylvania, have invented certain new and useful Improvements in Rail-Joints, of which the following is a specification.

This invention relates to certain new and useful improvements in rail joints. 10 The primary object of the invention is the provision of a secure joining means for the adjacent ends of railway rails whereby the rails may be readily attached together and thereafter separated at will.

15 A further object of the device is the provision of a rail joint for railway rails whereby the latter are locked in their operative longitudinal alinement by interengaging wedging means secured in position 20 by a tread joining device.

With these general objects in view and others that will appear as the nature of the invention is better understood, the same consists in the novel construction, combination 25 and arrangement of parts hereinafter more fully described, illustrated in the accompanying drawings, and then claimed.

In the drawings forming a part of this application and in which like designating 30 characters refer to corresponding parts throughout the several views:—Figure 1 is a side elevation of the present device operatively connecting two railway rails, the latter being broken away. Fig. 2 is a vertical longitudinal sectional view through the connected portion of the same. Fig. 3 is a horizontal longitudinal section taken upon line III—III of Fig. 2. Fig. 4 is a vertical transverse section taken upon line IV—IV 35 of Fig. 2. Fig. 5 is a perspective view of the two abutting end portions of the rails with the locking members detached. Fig. 6 is a perspective view of the tread connecting retaining member detached, and, Figs. 7 and 40 8 are different perspective views of the locking wedge employed with the device.

In the present form of rail joint it will be understood that railway rails such as 10 and 11 are adapted to be retained in longitudinal alinement, the abutting end portions 45 of two adjacent rails being preferably supported upon a railway tie 12. The opposite ends of each rail have the tread 13 and web 14 thereof cut-away in substantially similar manner with the exception that the receiving notches 15 formed in the webs 14

have outer oblique end walls 16 which are arranged slanting or diverging in opposite directions upon the opposite end portions of each rail. 60

By referring especially to Fig. 5 of the drawings it will be seen that the abutting end portions of the rails 10 and 11 have the treads 13 thereof vertically severed providing seats 17 upon the upper faces of the webs 14 adjacent each of the said treads while the notches 15 formed in the webs have the ends 16 of the notches laterally converging, thereby forming receiving sockets with their enlarged entrance ends at the same side of the track for the adjacent ends of the rails 10 and 11. The portion of the webs 14 at the ends of the rails lying outwardly of the notches 15 provide seats 18 of less height than the web seats 17 heretofore referred to. A connecting wedge or anchoring plate 19 is provided of the form illustrated in Figs. 7 and 8 of the drawings to conform to the cut-away or interrupted portions of the two webs 14 of the adjacent rail end portions. Said wedge plate is substantially U-shaped in form having opposite end portions 20 slidably receivable within the notches 15, the upper edge 21 of the plate at such times lying flush with the web seats 17 while the intermediate portion 22 of the lower face thereof is positioned upon the web seats 18. By this arrangement it will be seen that the wedge plate 19 supplies the cut-away portions of the webs 14 substantially completing such webs and forming a connection between the two rails, the plate ends 20 being retained within the notches 15 by their wedging insertion therein, an upward removal of the plate 19 being prevented by the incut arrangement of the notch walls 16 and the complementally formed inner faces 23 of the plate ends 20. 95

A locking rail 24 is arranged for overlying the end portions of the webs 14 and the wedge plate 19 as well as for supplying the interrupted portions of the rail treads 13, the said locking rail being of inverted U-shape in cross-section having a tread 25 positioned in alinement with the treads 13 of the rails 10 and 11 when the opposite parallel sides 26 of the locking rail overlie the plate 19 and rail webs 14 when operatively assembled as shown in Fig. 1 of the drawings. When the locking rail 24 is so positioned, the inner face 27 of the tread 25 is seated upon the web seats 17 and the

upper edge 21 of the wedge plate 19 while opposite flanges 28 are provided for the locking rail which rest upon the base flanges 29 of the rails 10 and 11. Suitable hold-
5 fast-devices, such as spikes 30 are positioned through alining perforations 31 in the flanges 28 and 32 in the flanges 29 being driven into the tie 12 whereby the locking rail 24 is firmly secured in its locking posi-
10 tion with the wedge plate and the joint between the webs of the rails entirely covered, the rails being also operatively maintained upon the tie 12.

What I claim as new is:—

- 15 1. A rail joint comprising adjacent rail ends having the terminal portions of the treads thereof severed forming seats upon the tops of the adjacent webs, the said webs being provided with notches having later-
20 ally tapered end walls and with the end portions of the webs cut-away forming seats of less height than the tops of the webs, a connecting plate wedgingly arranged within the said notches, and a locking rail over-
25 lying the said plate.
2. A rail joint comprising adjacent rail ends having the terminal portions of the treads thereof severed forming seats upon the tops of the adjacent webs, the said webs being provided with notches having later-
30 ally tapered end walls and with the end portions of the webs cut-away forming seats of less height than the tops of the webs, a wedge plate having end portions laterally
35 receivable within the said notches seated upon the end portions of the webs and having its upper face in alinement with the tops of the webs, and a locking rail between the treads of the said rails overlying the said
40 plate.
3. A rail joint comprising adjacent rail ends having the terminal portions of the

treads thereof severed forming seats upon the tops of the adjacent webs, the said webs being provided with notches having later-
45 ally tapered end walls and with the end portions of the webs cut-away forming seats of less height than the tops of the webs, a wedge plate having end portions laterally receivable within the said notches seated upon the end portions of the webs and having its upper face in alinement with the tops of the webs, an inverted U-shaped locking rail provided with a tread portion arranged in alinement between the treads of
50 the adjacent rails when operatively arranged seated upon the upper faces of the webs of the said rails, the said locking rail restrainingly overlying the said wedge plate when operatively positioned and having
55 opposite flanges overlying the base flanges of the connected rails.

4. A rail joint comprising in combination with the abutting ends of railway rails having severed tread and notched web portions, a wedge plate adapted for detachable connection with the said webs within the notched portions thereof, and a locking rail adapted for connecting the treads together completing the interrupted portions thereof when operatively arranged.

5. A rail joint comprising rail ends having the adjacent portions of their treads cut-away and with receiving notches in the adjacent portions of the webs thereof, a removable laterally insertible U-shaped wedge plate removably positioned within the said notches, and a locking rail for the said plate having a tread portion connecting the interrupted tread portions of the rails when operatively arranged.

In testimony whereof I affix my signature.

PETAR BAČKO.
